UNITED STATES PATENT OFFICE.

AUGUST P. LIGHTHILL, OF BOSTON, MASSACHUSETTS.

ATOMIZER.

SPECIFICATION forming part of Letters Patent No. 365,265, dated June 21, 1887.

Application filed January 18, 1886. Serial No. 188,980. (No model.)

To all whom it may concern:

Be it known that I, AUGUST P. LIGHTHILL, of Boston, in the county of Suffolk and State of Massachusetts, have invented certain new and useful Improvements in Atomizers or Nebulizers, of which the following is a specification.

My invention relates to what are commonly known as "atomizers," or those contrivances employed to vaporize liquids, such as antiseptic remedies or medicines of any character which are applied by transforming the liquid into a vapor or fog.

It is the object of my invention to improve the means employed to effect an absolute atomization or nebulization of liquids, so that they can be inhaled and drawn into the utmost recesses or cavities of the lungs or be forced into any part of the human system where air or other gas could be introduced, or be evenly and thoroughly distributed in the atmosphere of a sick chamber or any apartment which it may be desired to fumigate.

To the foregoing ends my invention consists in the improvements hereinafter described, and subsequently pointed out in the claims.

In the drawings hereto annexed, and forming a part of this specification, Figure 1 represents a side elevation of my improved atomizer. Fig. 2 represents a vertical section through the top and cover of the receptacle and the inlet and discharge tubes. Fig. 3 represents a vertical section of the air and liquid tubes at and a short distance beyond their jet- orifices. Fig. 4 represents a side elevation of a modified construction of a device embodying my improvements.

The same letters of reference indicate the same parts in all the figures.

In carrying out my invention, I provide a receptacle of any suitable character, preferably a glass bottle or jar of the form and character represented in Fig. 1, into which the liquid to be atomized is poured. Said receptacle is provided with a cover, *a*, suitably constructed to receive therethrough and support therein the air-inlet tube *b* and discharge-tube, *c*, as usual in this class of devices, except in the respects hereinafter noted.

I form the liquid-tube *d* as an integral part of the air-tube *b'*, forming the hollow or bore

of the former straight therethrough, while the bore or hollow of the latter is formed straight to a point near the jet-orifice where it is turned at a right angle thereto, and to the bore of the liquid-tube, as clearly represented in Fig. 3 of the drawings. By this construction I am enabled to construct the liquid and air tubes of an atomizer so that they constitute substantially a single straight stem and can be readily introduced through the neck of the smallest-sized bottles. I am also enabled by this construction to insure at all times a proper relationship of the jet-orifices to each other.

As shown in Fig. 2 of the drawings, I surround the inlet-tube *b* at the point where it passes through the top or cover of the jar or bottle with a rubber or other similar packing, *e*, which, while fitting closely around said tube, permits it to be adjusted vertically therein. It is to be noticed, also, that said tube *b* is eccentrically arranged in said cover or top—that is, it passes through the cover at a point to the side of the center thereof.

The neck of the bottle is externally screw-threaded at its upper end, and adapted to be received within the internally screw-threaded cap, by which construction the cap may not only be turned on the bottle-neck, but be raised and lowered thereon as well.

In the construction represented in Fig. 1 I have shown a bulb, *f*, as a means for forcing air through tube *b*, though any other means for the same purpose might be employed.

By the contrivance shown and described the atomized liquid is forced against the side of the jar, and thus broken into a thin cloud, or perfectly atomized or nebulized and rendered capable as it issues from the discharge-tube as a cloud of smoke of being inhaled or drawn into the lungs, or introduced into any part of the human system where it is possible for air or other gas to be forced.

When it is desired to have the atomized liquid impinge more directly against the side of the receptacle, and thus insure the breaking of the liquid into the finest possible particles and secure perfect nebulization, the cover of the receptacle may be rotated or turned, so as to bring the jet-nozzles nearer the side of the receptacle; or the same result may be accomplished where the sides of the vessel are angu-

lar or tapering in form by adjusting the tubes vertically in the cover of the receptacle, thus bringing the jet-nozzles nearer to the contracted sides of the bottle or jar.

- 5 In Fig. 4 I have shown a somewhat different construction and arrangement of parts and illustration of the manner of adjusting such differently-organized parts in different positions, in order to nebulize liquids to a greater 10 or less extent to meet the needs of particular cases, employing in this instance air and liquid tubes arranged with respect to each other as is common in atomizers and located within a funnel-shaped glass receptacle, the opening in 15 the smaller end of which affords a discharge-orifice for the nebulized liquid. In this arrangement the atomizer is supported on an arm, *g*, pivoted at *h* to the side of the support *i*. Said arm is properly guided and supported 20 so as to maintain the atomizer in proper position, its hinged connection with the frame providing for adjusting the atomizer so as to cause the atomized fluid to impinge more or less direct against the sides of the receptacle. 25 When the atomizer is in the position represented in said last-mentioned figure, the spray will be thrown against the side of the vessel near the mouth of the funnel; but if directed upward by rocking arm *g* backward on its pivot 30 it will come in more nearly immediate contact 35 with the side of the receptacle, and as a consequence with greater force.

Having thus described my invention, I claim—

- 35 1. In an atomizer constructed as a single and substantially straight stem, the liquid-tube formed below or beyond the air-tube, and the jet-orifices constructed at a point between the ends of the said substantially straight stem, 40 whereby the stem comprising the tubes may be inserted and operated in a small vessel or vial, or vessel or vial having a small neck, as and for the purposes set forth.

2. In an atomizer or nebulizer, the combination of a liquid-holding vessel or receptacle and cap or stopper to which the inlet or outlet tubes are attached, with the liquid-tube and air-tube constructed in a substantially straight line with the jet-orifices, which are located at a point between the ends of said substantially straight stem, as set forth. 45 50

3. In an atomizer, the combination, with the vessel or receptacle, of the liquid and air tubes arranged with respect to the vessel to cause the atomized fluid to impinge against the sides thereof, and means, substantially as hereinbefore described, for adjusting the jet-orifices of the tubes to bring the same nearer to or remove them farther from the side of the vessel, whereby the atomized liquid may be broken 55 into a cloud and the lightness or thinness of such cloud or nebulae may be varied, as set forth. 60

4. In an atomizer, the combination, with the receptacle and its rotary cover, of the liquid and air tubes constructed as a single and substantially straight stem, the liquid-tube being formed below or beyond the air-tube, and the jet-orifices being constructed at a point between the ends of said substantially straight 70 stem, said stem being supported eccentrically in and by said rotary cover, and means, substantially as hereinbefore described, whereby the cover may be rotated on the receptacle to bring the atomizing-point of the tubes nearer 75 to or remove it farther from the side of the vessel, as set forth.

In testimony whereof I have signed my name to this specification, in the presence of two subscribing witnesses, this 12th day of January, 1886.

AUGUST P. LIGHTHILL.
